UNITED STATES PATENT OFFICE.

WILLIAM M. SCOTT, OF PHILADELPHIA, PENNSYLVANIA.

REMOTE CONTROL APPARATUS.

1,022,644.

Specification of Letters Patent.

Patented Apr. 9, 1912.

Application filed June 29, 1910. Serial No. 589,477.

To all whom it may concern:

Be it known that I, WILLIAM M. Scott, a citizen of the United States, residing at Philadelphia, in the county of Philadelphia and State of Pennsylvania, have invented a new and useful Remote Control Apparatus, of which the following is a specification.

My invention relates to electric switching or control apparatus, and particularly to 10 electric switch or circuit breaker apparatus controlled from a more or less remote point; and my invention relates to a system in which a switch or circuit breaker is moved to normal position (as circuit closing position) by an electrically operated motive device, such as an electric motor, the switch or circuit breaker being adapted to be tripped either automatically or at the will of an operator whose control switch is located at a 20 point more or less remote from the switch or circuit breaker.

It is the object of my invention to provide, particularly in apparatus and in a system such as above referred to, means 25 which shall insure the disconnection of the motive device from the switch or circuit breaker when the switch or circuit breaker has reached normal position, even in the case where the circuit of the motive device is not 30 interrupted, or where the gearing or driving mechanism under the ordinary control sticks or refuses to become disconnected from the switch or circuit breaker, or in any other emergency.

35 With this object in view, my invention resides in an apparatus and system such as above referred to, in which means are provided for guaranteeing or insuring that the motive device shall be positively disconnected from the switch or circuit breaker even 40 in the event of failure of a switch to open the circuit of the motive device, in the event of the coupling between the motive device and the switch or circuit breaker failing to 45 become disconnected under the usual control, or in any other emergency.

My invention resides also in other features hereinafter described and pointed out in the claims.

50 For an illustration of one of the forms my invention may take, reference is to be had to the accompanying drawings, in which:

Figure 1 is a side elevational view of the switch or circuit breaker and its operating 55 motor, portions being shown in section.

Fig. 2 is a side elevational view, on larger scale, of the motor control switch. Fig. 3 is a top plan view of the localizing and other control switches. Fig. 4 is a plan view showing the conducting and insulating parts of the movable member of the switch shown in Fig. 3. Fig. 5 is a diagram of the circuits and connections of one arrangement of my invention.

In Fig. 1, a base or switchboard 1, preferably of insulating material, such as marble or slate, has secured thereon the main terminal blocks 2 and 3 in electrical communication with the studs 4 and 5, respectively, extending through the base 1 and provided with nuts 6. Adapted to engage and bridge the main terminals 2 and 3, is the main movable contact member 7, here representing a laminated contact member, secured upon the arm 8 pivoted at 9 to the housing or bracket 10. A spring 11, in tension in the position shown in Fig. 1, is connected at its one end to the pivoted arm 8, and at its other end to the member 22. Secured upon and in electrical communication with the upper terminal block 2 are the stationary metallic shunt contact 12 and the stationary shunt carbon contact 13, the latter pivoted at 14 on the bracket 15. Carried by the arm 8 are the movable metallic shunt contact 16 and the movable carbon shunt contact 17 adapted to engage, respectively, the contacts 12 and 13. The contacts 16 and 17 are in permanent electrical communication with the lower main terminal block 3 by the flexible conductor 18. Pivoted at 19 on the arm 8 is the roller 20 engaged by the cam surface 21 on the cam member 22 pivoted to the housing or bracket 10 at 23 and having the outward extension 24 carrying the operator's grip or handle 25. On a projection 26 on the lever 24 is pivoted a roller 27 adapted to be engaged by the latch 28 pivoted to the bracket or housing 10 at 29, the latch 28 having a rear extension formed as a jaw 30 loosely embracing the pin 30 for limiting the movement of the latch 28. Pivoted at 29 is the latch actuator 31 similarly limited as to its movement and carrying an adjustable screw 32 adapted to strike upon the top of the latch 28. The latch 28 and its actuator 31 are urged in counter-clockwise direction by a spring or springs, not shown, coiled about pivot 29. The latch actuator 31 has a tail 33 disposed in the path of 110

travel of the member 34 pivoted at 35 and carrying the armature 36 of an electro-magnetic tripping device which may be a simple overload coil, as 37, Fig. 5, or which may 5 be any suitable winding disposed either in the same circuit with the main terminals 2 and 3, or in any other circuit, the armature 36 being responsive to any predetermined electrical condition. Attached to the tail 10 33 of the latch actuator 31 is a rod 38 disposed in the path of travel of the armature 39 pivoted at 40 and coöperating with the poles 41 of another electro-magnet whose winding is 42.

15 Supported upon the base 1 below the switch or circuit breaker above described, or in any other suitable position, is a motive device, such as the electric motor M on the upper end of whose shaft 43 is secured 20 one member 44 of a universal joint whose other member 45 is secured upon the shaft 46, whose upper end has a bearing in the member 47 carried by the link 48 pivoted at its lower end at 49, and at its upper 25 end at 50 to the toggle link 51 which is, in turn, pivoted at 52 to the second toggle link 53 pivoted at 54 to a bracket or housing 55.

Secured upon the shaft 46 and rotated 30 by motor M is the worm 56 adapted to mesh with the gear 57 pivoted at 58 on the bracket or housing 55. Attached to the gear member 57 is a crank 59 to which there is pivoted at 60 a rod 61 having more or less lost motion with respect to the member 62 within 35 which is inclosed the head 63 of the rod 61, a spring 64 engaging under the head 63 and against the bottom of the member 62. The member 62 is pivoted to the operating 40 lever 24 at 65.

Supported on the housing or bracket 55 is a jacketed solenoid whose winding 66 surrounds the magnetizable core 67 carrying the rod 68 having near its upper end a 45 elongated opening 69 in which engages a pin 70 carried by the toggle link 53. At the upper end of the rod 68 is a stop or buffer surface 71 adapted to engage the under side of the member 72 extending across 50 the bracket or housing 55, or any other part fixed to housing 55. Supported upon but insulated from the toggle link 53 are the conducting portions 74 and 75 (in electrical communication with each other) of the movable 55 member of control switches, the insulating material 76 being provided for purposes hereinafter described. Supported upon the member 72 extending across the top of the housing 55 and insulated therefrom by 60 material 77 are the brushes 78, 79, 80 and 81, all insulated from each other.

Pivoted at 58, independently of the gear wheel 57, is a bell crank consisting of the arms 82 and 83, a lug 84 carried by the gear 65 wheel 57 is adapted to engage the bell

crank 82, 83 in a clockwise rotation of the gear wheel 57, as viewed in Fig. 1, and a lug 85 carried by the gear wheel 57 is adapted to engage the bell crank 82, 83 in counter-clockwise movement of the gear wheel 57. The arm 83 of the bell crank is adapted to engage, under the conditions hereinafter referred to, the end 86 of the toggle link 51; and the arm 82 of the bell crank has pivoted thereto at 87 a rod 88 pivoted at 89 to the arm 90, connected to the spring winding member of the motor control switch shown in Fig. 2. The length of the rod 88 may be adjusted by means of member 91.

70 The motor control switch 92, as shown in Fig. 2, is secured upon the side of the housing 55 and comprises the movable contact member 93 adapted to engage the stationary contact member 94 which may yield in opposition to spring 95. When the switch 92 is closed, with the contacts 93 and 94 in engagement, it is locked, the actuating spring 96 being previously wound up by the opening of the main switch or circuit breaker, ready to snap the contact 93 away from contact 94 when released or unlocked, this switch being preferably locked only in circuit closing position.

75 Between the main terminal blocks 2 and 3 of the main switch or circuit breaker there are secured upon the base 1 the separated contacts 97 and 98 adapted to be bridged by the bridging contact 99 movable with the main laminated contact member 7. When the main switch or circuit breaker is 80 open the bridging contact 99 moves away from the contacts 97 and 98 to interrupt the circuit of the tripping coil 42 controlled thereby.

85 Referring to Fig. 5, 100 and 101 are the positive (for example) and the negative (for example) conductors, respectively, of a circuit or network from which energy is derived for controlling the main switch or circuit breaker, whose terminals 2 and 3 90 communicate by conductors 2^a and 3^a, respectively, with the same network or with any other circuit or network. And the switch's or circuit breaker's own tripping coil 37 may be connected in the same circuit with the main switch or circuit breaker or in any other circuit, and may be responsive to any predetermined electrical condition.

95 From conductor 100 extends conductor 102 to the lever 103 of the operator's switch D, which may be located at a point more or less remote from the main switch or circuit breaker which it is to control. The operating lever 103 carries the contacts 104 and 105 in electrical communication with each other and with the conductor 102 and adapted to engage, respectively, the stationary contacts 106 and 107. The contacts 104 and 105 are normally in the position shown 100

in Fig. 5 out of engagement from contacts 106 and 107, a spring or gravity being utilized to return the operator's lever 103 to the central position shown. Between contact 106 and conductor 102 are connected the resistance 108 and the indicating lamp 109, it being understood that the resistance 108 may be omitted when the apparatus is used in connection with a low potential circuit. 10 Similarly, between contact 107 and conductor 102 are connected the resistance 110 and the indicating lamp 111, it being understood that the resistance 110 may be omitted on low potential circuits. From contact 106 15 extends conductor 112 to one terminal of the trip coil 42 whose other terminal connects to the contact 97, the contact 98 connecting with conductor 113 connected with the negative conductor 101. The conductor 20 113 extends also to the contact 94 of the motor control switch, and the movable contact 93 of the motor control switch is connected by conductor 114 with one brush 115 of the armature 116 of the motor M. The 25 other brush 117 is connected to one terminal of the field winding 118 of the motor M and also to one terminal of the solenoid winding 66. The other terminal of the field winding 118 connects by conductor 119 with the brush 80. The other terminal of the 30 solenoid winding 66 connects by conductor 120 with brush 81, the resistance 121 being connected across the brushes 80 and 81 by conductors 119 and 120. Brush 79 is connected by conductor 102 with the positive conductor 100, and brush 78 is connected by conductor 122 with contact 107 of the operator's switch D.

The operation is as follows: With the 40 main switch or circuit breaker in circuit closing position as shown in Fig. 1, upon the occurrence of any predetermined electrical condition in the circuit in which its tripping coil 37 is connected, the armature 36 will be attracted and rotated in a counter-clockwise direction about its pivot 35, as viewed in Fig. 1, causing the member 34 to strike the under side of the tail 33 of the latch actuator member 31 to move the same 45 in opposition to its spring and to cause the screw 32 to engage upon the top of the latch 28 to depress the same in opposition to its spring to release roller 27, with resultant unlocking of the switch or circuit breaker. 50 The spring 11 being under tension, the main contact member swings outwardly on its pivot 9 away from contacts 2 and 3, the operating member 22 and its lever handle 24 rotating in a counter-clockwise direction 55 about the pivot 23. After the main contact 7 separates from main terminal blocks 2 and 3, contact 16 separates from contact 12, and finally, contact 17 separates from contact 13, the final arc occurring at 60 these carbon contacts. The contacts 7, 16

and 17 continue to swing outwardly from the base but about pivot 9 until the circuit is completely ruptured, in which position the operating lever 24 is elevated, the lever 24 having carried upwardly with it the connecting rod 61 and rotated the gear wheel 57 in a counter-clockwise direction about its pivot 58, gear 57 being free to rotate independently of actuation or control by the motor M, since the worm 56 is out of mesh. 70 When the main switch or circuit breaker is in the closed position, as shown in Fig. 1, the switch 97, 98, 99, is closed and there is a circuit from positive conductors 100 and 102 through lamp 109, resistance 108, contact 106, conductor 112, tripping coil 42, switch 97, 98, 99, conductor 113, to the negative conductor 101. Current flows through lamp 109 causing it to glow and indicate at the distant switch D that the main switch or 80 circuit breaker is closed and may be tripped by the tripping coil 42. If the operator desires to trip the main switch or circuit breaker he moves the lever 103 to bring contacts 104 and 106 into engagement with each 85 other, whereupon lamp 109 and resistance 108 are short circuited, thus removing from the circuit of the trip coil 42 considerable 90 resistance, with the result that a greater current flows through the coil 42, such increased 95 current being now sufficient to cause the upward attraction of armature 39 about its pivot 40, causing the armature 39 to lift the rod 38 and, therefore, the tail 33 of the latch actuating member 31, which then depresses the latch 28 to unlock the main 100 switch or circuit breaker, as before described, whereupon the main switch or circuit breaker flies to open circuit position. As the main switch or circuit breaker moves 105 to circuit interrupting position, switch 97, 98, 99 is opened and, therefore, no current will flow through lamp 109; the lamp being now dark indicates that the main switch or circuit breaker is in open circuit position. 110 As the main switch or circuit breaker opens, the gear wheel 57 is rotated in a counter-clockwise direction, as viewed in Fig. 1, due to the upward travel of the connecting rod 61 attached to the lever 24. 115 The lug 85 on the gear wheel 57 engages the arm 83 of the bell crank lever moving the bell crank in a counter-clockwise direction about the pivot 58 rotating the arm 90 of the motor switch in such direction as to 120 bring contact 93 into engagement with contact 94, and to lock the same in engagement by detent 96. There is, then, a closed path from the positive conductor 100 through conductor 102, lamp 111, resistance 110, contact 107, conductor 122, brush 78, contact 74, contact 75, (contacts 74 and 75 being in permanent electrical connection with each other) brush 81, conductor 120, thence 125 through winding 66 in parallel with resist- 130

ance 121 and motor field winding 118, motor armature 116, and through motor switch 93, 94, which is now closed, as above described, through conductor 113 to the 5 negative conductor 101. The lamp 111 now glows and indicates that the parts are in condition to allow closure of the same by the motor M.

To close the main switch or circuit 10 breaker, the operator moves the lever 103 of the distant switch D to bring contact 105 into engagement with contact 107, whereupon the lamp 111 and resistance 110 are short circuited, with resultant increase of 15 current through the circuit last traced through the motor M. The resultant increased current suffices to energize the solenoid whose winding is 66 to a degree to lift the core 67 and to move the toggle link 53 20 upwardly, with the result that the worm 56 is brought into mesh with the gear 57. The upward travel of the core 67 is limited by the stop 71 engaging on the under side of the plate 72 extending across the housing 55. 25 The toggle, however, has been raised to the position where the pivots 54, 52 and 50 are in the same straight line, or the pivot 52 slightly above the imaginary straight line joining the centers of pivots 54 and 50. Simultaneously with the energization of winding 66 the motor field 118 and motor armature 116 have been energized and the motor starts to rotate slightly before the worm 56, rotated by the motor M, comes into mesh 30 with the wheel 57.

As the toggle link 53 has been rotated in a counter clockwise direction about its pivot 54 by the solenoid core 67, as above described, the brush 78 passes off of contact 74 40 on to insulation 76, simultaneously brushes 79 and 80 pass off of insulation 76 on to the contact 75, and the brush 81 continues in engagement with contact 75. The result is that resistance 121 is short circuited and the contacts 105 and 107 of the distant operator's switch D are robbed of control. That is to say, once the closing movement of the main switch or circuit breaker has been initiated by the distant switch, the closing movement 45 continues in spite of the distant switch, since now the current will flow from positive conductor 100, through conductor 102, through brush 79, contact 75, conductor 120, through the solenoid winding 66, and through brush 50 80 and conductor 119 through the motor field 118. And even if the operator at the distant switch should immediately separate contacts 105 and 107 after having initiated the closing movement, the closing movement 55 60 will continue without possibility of interference by distant switch D.

As the motor M continues its rotation, gear wheel 57 is rotated in a clockwise direction about its pivot 58 causing rod 61 to be 65 pulled downwardly, with a resultant clock-

wise movement of lever 24 and cam member 22 in a clockwise direction about pivot 23, the cam surface 21 engaging the roller 20 and moving the arm 8 in a counter-clockwise direction about its pivot 70 9, first bringing carbon 17 into engagement with carbon 18, then contact 16 into engagement with contact 12, and finally, the bridging contact 7 into engagement with the main terminal blocks 2 and 3, whereupon the latch 28, urged upwardly by its spring, engages roller 27 to lock the main switch or circuit breaker in closing position. With this movement of the gear wheel 57 the lug 84 engages the arm 83 of the bell crank, rotating the same in a clockwise direction about its pivot 58 causing the arm 82 to push the rod 88 toward the left acting on the arm 90 to trip the snap switch 93, 94, with their resultant quick separation to break the circuit of the motor M and also the circuit of the solenoid winding 66. The motor M is accordingly deenergized, as is also the solenoid whose winding is 66, and the core 67 drops. Inasmuch as the downward collapse of the toggle 51, 53, removes the worm 56 from mesh with wheel 57, the construction shown is such that the weight of the core and attached parts is exerted in a direction to move the worm wheel out of mesh, that is to say, to the safe position. And inasmuch as the toggle 51, 53 may be slightly overtraveled, as above stated, the core 67 falls a short distance, due to the slot 69, before the pin 70 is engaged, delivering 100 a blow to pin 70. When the pin 70 is engaged it carries the toggle downwardly across the dead center position, and the further collapse of the toggle is insured by the action of the weight of core 67 and attached 105 parts to positively remove the worm 56 from mesh with gear 57.

During the collapse of the toggle, the contacts 74 and 75 and insulation 76 are moved in a clockwise direction about pivot 54, with the result that brush 78 rides off of insulation 76 on to contact 74, brushes 79 and 80 leave contact 75 and rest on insulation 76, while brush 81 continues in engagement with contact 75. The motor switch 93, 94 being now open, the circuit through the lamp 111 is interrupted and as this lamp is extinguished it indicates to the operator at the distant switch D that the main switch or circuit breaker has reached circuit closing 110 position. And as the main switch or circuit breaker reaches circuit closing position, switch 97, 98, 99, is again closed with the result that lamp 109 will again glow giving a further indication that the main switch 115 or circuit breaker is closed.

If, for any reason the motor switch 93, 94 should fail to open, as the main switch or circuit breaker reaches full circuit closing position, the motor M would continue to 130

rotate and continue to pull down on the rod 61, with the result that some part of the apparatus would be strained or damaged, even to the extent of making it impossible 5 for the main switch or circuit breaker to open even when tripped by its own tripping mechanism. The motor M becomes disconnected from the gear 57, however, due to the arm 83 of the bell crank being positively driven by gear 57, the outer end of 10 the arm 83 engaging the end 86 of the toggle lever 51 to positively collapse the toggle and remove the worm 56 from mesh with wheel 57 a moment after the motor switch 15 93, 94 should have opened. The bell crank serves in this case as an emergency device to positively mechanically disconnect the motor from the main switch or circuit breaker very promptly after the main switch 20 or circuit breaker has reached full circuit closing position. Or, if the worm 56 should stick in mesh with the gear 57 for any reason, even in the case where the motor switch 93, 94 has opened, and the momentum of the 25 motor armature would continue to pull downwardly on the rod 61, the arm 83 of the bell crank will positively disengage the worm 56 from the gear 57. Or, in fact, in all cases where the electrical and mechanical 30 controls fail, the bell crank 83 will positively disengage the worm 56 from the gear 57, thus positively disengaging the motor M from the main switch or circuit breaker when the latter has reached normal position, 35 as, for example, circuit closing position.

The resistance 121, in circuit only at the initiation of the closing movement of the main switch or circuit breaker, serves to force a greater current to flow through solenoid winding 66, and, therefore, more powerfully energize the solenoid 66 at the moment of starting than during the later periods of the closing movement. It is during the early moments of the circuit closing movement that the solenoid 66 should be most powerfully energized to start and lift the core 67 and attached parts. This resistance serves also to make the motor M start more smoothly and gradually. After the resistance 40 121 is cut out, the current through the solenoid winding 66 is still sufficient to hold the core 67 in the elevated position. Resistance 121 also serves to prevent the motor M from racing in case the motor switch 93, 94 fails to open.

The motor switch contact 94 may be yieldingly mounted, as above described, so that with different adjustments of the length of the rod 61, or with different adjustments of other parts, the contacts 93 and 94 will nevertheless engage; and this yielding mounting of contact 94 obviates the necessity for nicely positioning the motor switch contacts.

What I claim is:

1. The combination with a main switch or

circuit breaker, of a motive device for moving the same to normal position, said switch or circuit breaker movable to another position independently of actuation or control by said motive device, a disengageable mechanical connection between said motive device and said main switch or breaker, a switch controlling said motive device, and a member having lost motion connection with said motive device through said mechanical connection for actuating said switch to de-energize said motive device when said main switch or breaker has reached normal position. 70

2. The combination with a main switch 80 or circuit breaker, of a motive device for moving the same to normal position, said main switch or circuit breaker movable to another position independently of actuation or control by said motive device, a disengageable mechanical connection between said motive device and said main switch or breaker, a switch controlling said motive device, and a member having lost motion connection with the movable member of said 85 main switch or circuit breaker for actuating said switch when said main switch or breaker moves to said other position. 90

3. The combination with a main switch or circuit breaker, of a motive device for actuating the same, a disengageable mechanical connection between said motive device and said main switch or breaker, a switch for breaking the circuit of said motive device when said main switch or circuit breaker 100 reaches normal position, and a member actuated by said motive device for breaking said mechanical connection upon failure of such switch to break the circuit of said motive device. 105

4. The combination with a main switch or circuit breaker, of a motive device for moving the same to normal position, electro-responsive means for mechanically connecting said motive device and said main switch or breaker, a switch for deenergizing said electro-responsive means to disconnect said motive device from said main switch or breaker when the latter has reached normal position, and a member actuated by said 110 motive device for disconnecting said motive device from said main switch or breaker upon failure of said motive device to become disconnected from said main switch or breaker upon deenergization of said electro-responsive means. 115

5. The combination with a main switch or circuit breaker, of a motive device for actuating the same, a disengageable mechanical connection between said motive device 125 and said main switch or breaker, a switch actuated by said motive device while said motive device and said main switch or breaker are mechanically connected to de-energize said motive device, and a member 130

- actuated by said motive device for breaking said mechanical connection when said switch fails to deenergize said motive device.
6. The combination with a switch, of a motive device therefor, a disengageable mechanical connection between said motive device and said main switch, and a member driven by said motive device when said mechanical connection is in engagement, said member having lost motion with respect to said main switch and adapted to break said mechanical connection.
7. The combination with a switch, of a motive device therefor, a member driven by said motive device, a second member driven by said member, a third member driven by said second member and adapted to disengage said first and second members from each other, and a switch for deenergizing said motive device before disengagement of said first and second members.
8. The combination with a switch, of a motive device therefor, a member driven by said motive device, a second member driven by said member, and a third member having lost motion with respect to and driven by said second member for disconnecting said first and second members from each other.
9. The combination with a main switch or circuit breaker, of a motive device therefor, a disengageable mechanical connection between said motive device and said main switch or breaker, a switch controlling said motive device, and a member for operating said switch and for breaking said mechanical connection upon failure of said switch to deenergize said motive device.
10. The combination with a switch, of a motive device therefor, disengageable driving and driven members intervening between said motive device and said switch, and a member having lost motion connection with and driven by said driven member for disengaging said driving and driven members.
11. The combination with a main switch or circuit breaker, of a motive device therefor, driving and driven members intervening between said motive device and said main switch or circuit breaker, a switch controlling said motive device, and a member having lost motion with respect to and driven by said driven member for actuating said switch and thereafter disconnecting said driving and driven members from each other.
12. The combination with an electric switch, of a motive device for moving the same to normal position, a disengageable connection between said motive device and said switch, the movement of said switch to abnormal position being independent of either actuation or control by said motive device, and a member actuated by said motive device for disconnecting the same from said switch when said switch has reached normal position.
13. The combination with a main switch, of a motor for actuating the same, a worm and gear intervening between said motor and switch, means for throwing said worm into mesh with said gear, a switch actuated when said main switch reaches normal position for controlling said motor, and a member for throwing said worm and gear out of mesh when said switch fails to deenergize said motor.
14. The combination with a main switch, of a latch for locking the same in normal position, a motor for moving said main switch to normal position, disengageable gearing intervening between said motor and said switch, a switch for deenergizing said motor actuated when said main switch reaches normal position and is latched, and a member driven by said motor when said gearing is in engagement for disengaging said gearing after said motor-controlled switch has been actuated.
15. The combination with a switch, of a motor for actuating the same, disengageable gearing intervening between said motor and said switch, and an independent member driven by said motor through said gearing when in engagement for disengaging said gearing upon overtravel of said motor.
16. The combination with a switch, of a motor, disengageable gearing intervening between said motor and said switch, and a member having lost motion with respect to and driven by the part of the disengageable gearing connected with said switch for disengaging said gearing upon overtravel of said motor.
17. The combination with a main switch or circuit breaker, of a motor, disengageable gearing intervening between said motor and said main switch or breaker, a motor switch, and a member driven by the part of said disengageable gearing connected with said main switch or breaker for actuating said motor switch and for disengaging said gearing.
18. The combination with a main switch or circuit breaker, of a motor, disengageable gearing intervening between said motor and said main switch or breaker, a motor switch, and a member having lost motion with respect to and driven by the part of said disengageable gearing connected with said main switch or circuit breaker for actuating said motor switch and for disengaging said gearing.
19. The combination with a main switch or circuit breaker, of a motor, disengageable gearing intervening between said motor and said main switch or breaker, a motor switch, and a member driven by the part of said disengageable gearing connected with said main switch or circuit breaker for actuating said motor switch and for disengaging said gearing.

- main switch or breaker for actuating said motor switch and for disengaging said gearing, the movement of said main switch or breaker when disconnected from said motor serving to actuate said member to close said motor switch. 5
20. The combination with a main switch or circuit breaker, of a motor, disengageable gearing intervening between said motor and said main switch or breaker, a motor switch, and a member having lost motion with respect to and driven by the part of said disengageable gearing connected with said main switch or circuit breaker for actuating said 10 motor switch and for disengaging said gearing, the movement of said main switch or breaker when disconnected from said motor serving to actuate said member to close said motor switch. 15
20. 21. The combination with a switch, of a motor, a worm and gear intervening between said motor and said switch, and a member driven by said gear for moving said worm out of mesh. 25
25. 22. The combination with a switch, of a motor, a worm and gear intervening between said motor and said switch, and a member driven by said gear for moving said worm out of mesh when said motor overtravels. 30
30. 23. The combination with a switch, of a motor, a worm and gear intervening between said motor and said switch, and a member having lost motion with respect to and driven by said gear for moving said worm out of mesh. 35
24. The combination with a switch, of a motor, a worm and gear intervening between said motor and said switch, and a member having lost motion with respect to and driven by said gear for moving said worm out of mesh when said motor overtravels. 40
25. 24. The combination with a switch, of a motor, a worm and gear intervening between said motor and said switch, a toggle controlling said worm, and a member actuated by said motor for breaking said toggle to disengage said worm from said gear. 45
26. The combination with a switch, of a motor, a worm and gear intervening between said motor and said switch, a toggle controlling said worm, and a member actuated by said gear for breaking said toggle to disengage said worm from said gear. 50
55. 27. The combination with a main switch or circuit breaker, of a motor, a worm and gear intervening between said motor and said main switch or breaker, a toggle controlling said worm, electro-magnetic means controlling said toggle, a switch controlling said electro-magnetic means, and a member having lost motion with respect to and driven by said gear for breaking said toggle to disconnect said worm and gear and for opening said switch. 55
20. The combination with a switch, of a motor, a worm and gear intervening between said motor and said switch, a pivoted lever for disengaging said worm from said gear, and means on said gear for engaging said lever. 70
29. The combination with a switch, of a motor, a worm and gear intervening between said motor and said switch, a pivoted lever for disengaging said worm from said gear, and means on said gear for engaging said lever. 75
30. The combination with a switch, of a motor, a worm and gear intervening between said motor and said switch, a pivoted lever for disengaging said worm from said gear, and means on said gear for engaging said lever upon overtravel of said motor. 80
31. The combination with a main switch or circuit breaker, of a motor, a worm and gear intervening between said motor and said main switch or circuit breaker, a motor control switch, a lever for actuating said motor switch and for disengaging said worm from said gear, and means on said gear for engaging said lever in one direction to close said motor switch, and in opposite direction to engage said lever to first control said motor switch and thereafter disengage said worm from said gear upon overtravel of said motor. 85
32. The combination with a switch, of a motor, a worm and gear intervening between said motor and said switch, a lever pivoted concentrically with said gear, and means on said gear for engaging said lever to disengage said worm and gear. 90
33. The combination with a switch, of a motor, a worm and gear intervening between said motor and said switch, a lever pivoted concentrically with said gear and having lost motion with respect thereto, and means on said gear for engaging said lever upon overtravel of said motor to disengage said worm from said gear. 95
34. The combination with a main switch or circuit breaker, of a motor, a worm and gear intervening between said motor and said main switch or circuit breaker, a motor switch, a lever pivoted concentrically with said gear, and means on said gear for engaging said lever to control said motor switch and to thereafter disengage said worm from said gear upon continued movement of said motor. 100
35. The combination with a switch, of a motor, a worm and gear intervening between said motor and said switch, a toggle for moving said worm, an electro-magnetically actuated member for extending said toggle to overtraveled position to hold said worm 105
26. The combination with a main switch or circuit breaker, of a motor, a worm and gear intervening between said motor and said main switch or breaker, a toggle controlling said worm, electro-magnetic means controlling said toggle, a switch controlling said electro-magnetic means, and a member having lost motion with respect to and driven by said gear for breaking said toggle to disconnect said worm and gear and for opening said switch. 110
28. The combination with a main switch or circuit breaker, of a motor, a worm and gear intervening between said motor and said main switch or breaker, a toggle for moving said worm, an electro-magnetically actuated member for extending said toggle to overtraveled position to hold said worm 115
29. The combination with a switch, of a motor, a worm and gear intervening between said motor and said switch, a toggle for moving said worm, an electro-magnetically actuated member for extending said toggle to overtraveled position to hold said worm 120
30. The combination with a switch, of a motor, a worm and gear intervening between said motor and said switch, a toggle for moving said worm, an electro-magnetically actuated member for extending said toggle to overtraveled position to hold said worm 125
31. The combination with a switch, of a motor, a worm and gear intervening between said motor and said switch, a toggle for moving said worm, an electro-magnetically actuated member for extending said toggle to overtraveled position to hold said worm 130

in mesh with said gear, and a member actuated by said motor upon its overtravel for breaking said toggle.

36. The combination with a main switch, 5 of a motor for actuating the same, a worm and gear intervening between said motor and said switch, a toggle for moving said worm, a member for extending said toggle to overtraveled position to hold said worm 10 in mesh with said gear, said member having lost motion with respect to said toggle, an electro-magnetic winding for actuating said member, and an auxiliary switch controlling simultaneous energization of said motor and 15 said electro-magnetic winding, and means actuating said auxiliary switch after predetermined movement of said main switch, whereby said motor and said electro-magnetic winding are deenergized and said member strikes a blow to collapse said toggle to 20 positively disengage said worm and gear.

37. The combination with an electric switch, of a gear for actuating the same, a worm for driving said gear, a motor for 25 driving said worm, a universal joint between the shaft of said motor and said worm, a toggle connected to said worm, electro-magnetic means for actuating said toggle to bring said worm into mesh with said gear, 30 and a member driven by said gear for disengaging said worm from said gear upon overtravel of said motor.

38. The combination with a main switch, 35 of a motor for actuating the same, an operator's switch for controlling said motor, a worm and gear intervening between said motor and said main switch, means for shifting said worm into and out of mesh with said gear, a switch actuated by said 40 worm shifting means for maintaining the circuit of said motor closed independently of said operator's switch, and a member driven by said motor for disengaging said worm from said gear upon overtravel of 45 said motor.

39. The combination with a main switch, 50 of a motor for actuating the same, a worm and gear intervening between said motor and said main switch, means for throwing said worm into mesh with said gear and out 55 of mesh when said motor stops, a motor circuit switch actuated by said motor to interrupt the circuit of said motor, a connection from said main switch to said motor switch to restore the circuit of said motor upon the 60 opening of said main switch, and a member for disengaging said worm from said gear upon overtravel of said motor.

40. The combination with an electric 65 switch, of a motor, a worm and gear intervening between said motor and said switch, a toggle having a link attached to said worm, and a member driven by said motor to engage a toggle link to disengage said worm from said gear.

41. The combination with an electric switch, of a driving motor therefor, a disengageable mechanical connection between said motor and said switch, electro-magnetic means controlling said mechanical connection, a resistance in circuit with said motor, and the winding of said electro-magnetic means connected in parallel with a conductor including said resistance. 70

42. The combination with an electric 75 switch, of a driving motor therefor, a disengageable mechanical connection between said motor and said switch, electro-magnetic means controlling said mechanical connection, a resistance in circuit with said motor, 80 the winding of said electro-magnetic means connected in parallel with a conductor including said resistance, and a switch controlled by said electro-magnetic means after current has been admitted to said motor 85 for cutting out said resistance.

43. The combination with an electric switch, of a driving motor therefor, a disengageable mechanical connection between said motor and said switch, electro-magnetic 90 means controlling said mechanical connection, and a switch controlled by said electro-magnetic means for cutting out said resistance.

44. The combination with an electric 95 switch, of a driving motor therefor, a disengageable mechanical connection intervening between said motor and said switch, electro-magnetic means controlling said mechanical connection, a resistance associated with the field winding of said motor, 100 and the winding of said electro-magnetic means connected in parallel with said field winding and said resistance.

45. The combination with an electric 105 switch, of a driving motor therefor, a disengageable mechanical connection intervening between said motor and said switch, electro-magnetic means controlling said mechanical connection, a resistance associated with the field winding of said motor, 110 and the winding of said electro-magnetic means connected in parallel with said field winding and said resistance, and means for cutting out said resistance after said 115 motor starts.

46. The combination with an electric switch, of a driving motor therefor, a disengageable mechanical connection intervening between said motor and said switch, electro-magnetic means controlling said mechanical connection, a resistance associated with the field winding of said motor, 120 and a switch controlled by said electro-magnetic means for cutting out said resistance. 125

47. The combination with an electric switch, of a motor for driving the same, a disengageable mechanical connection between said motor and said switch, electro- 130

magnetic means controlling said mechanical connection, a resistance connected in series with a field winding of said motor, and the winding of said electro-magnetic means connected in parallel with said resistance and field winding.

48. The combination with an electric switch, of a motor for driving the same, a disengageable mechanical connection between said motor and said switch, electro-magnetic means controlling said mechanical connection, a resistance connected in series with a field winding of said motor, and the winding of said electro-magnetic means connected in parallel with said resistance and said field winding, and means controlled by said electro-magnetic means operative upon the starting of said motor for cutting out said resistance.
49. The combination with an electric switch, of a motor, a disengageable mechani-

cal connection intervening between said motor and said switch, a toggle controlling said mechanical connection, and a switch controlling said motor having a movable contact carried by a member of said toggle. 25

50. The combination with an electric switch, of a motor, a disengageable mechanical connection intervening between said motor and said switch, a toggle controlling said mechanical connection, and a plurality of switches controlling said motor and the actuation of said mechanical connection having their movable contacts carried by a member of said toggle. 30

In testimony whereof I have hereunto affixed my signature in the presence of the two subscribing witnesses.

WILLIAM M. SCOTT.
